JOSEPH W. NETHERY, OF INDIANAPOLIS, INDIANA, ASSIGNOR TO THE NETHERY HYDRAULIC VALVE COMPANY, OF INDIANAPOLIS, INDIANA, NEW YORK, N. Y., AND JERSEY CITY, NEW JERSEY, A CORPORATION OF NEW JERSEY.

FLUID-FLOW-CONTROLLING DEVICE.

SPECIFICATION forming part of Letters Patent No. 713,788, dated November 18, 1902.

Application filed January 21, 1902. Serial No. 90,668. (No model.)

To all whom it may concern:

Be it known that I, JOSEPH W. NETHERY, a citizen of the United States, residing at Indianapolis, in the county of Marion and 5 State of Indiana, have invented certain new and useful Improvements in Fluid-Flow-Controlling Devices, of which the following is a specification.

The object of my present invention is to 10 provide a means which when a fluid-outlet is opened will permit the flow to continue for a certain predetermined period (or quantity) and then automatically shut it off. An apparatus embodying my said invention will be 15 first fully described and the novel features thereof then pointed out in the claims.

Referring to the accompanying drawings, which are made a part hereof, and on which similar reference characters indicate similar 20 parts, Figure 1 is a central vertical sectional view through so much of a fluid-delivering apparatus as embodies my said invention and illustrates one type of said invention; Figs. 2 and 3, horizontal sectional views, on an enlarged scale, as seen when looking in the directions indicated by the arrows from the dotted lines 2 2 and 3 3, respectively, in Fig. 1; Fig. 4, a view similar to Fig. 1, illustrating an alternative construction; Fig. 5, a view 25 similar to a portion of Fig. 4, but on an enlarged scale; and Figs. 6 and 7, horizontal sectional views, on an enlarged scale, as seen when looking in the direction indicated by the arrows from the dotted lines 6 6 and 7 7, respectively, in Figs. 4 and 5.

The pipe 10 is a fragment of any ordinary fluid-conveying pipe and leads from any suitable source of supply. (Not shown.) From a suitable fitting secured to the end of this 40 pipe two conduits lead to any ordinary fluid-outlook, as a cock or faucet. One of these may be a plain conduit, having no special peculiarities, or it may be constructed specially, as for convenience or to improve the 45 appearance. In Fig. 4 one of these conduits is shown in line with the pipe 10 and the other to one side and connected thereto by suitable fittings, thus forming a fluid-conduc-

tor arranged as a by-pass around the devices embodying the construction peculiar to my 50 invention. In the construction illustrated especially in Fig. 1 the fluid-conductor is larger than and incloses a smaller tube containing the devices peculiar to my invention. Otherwise the two forms are substantially 55 the same, the differences being of a mechanical character and unimportant. As is entirely obvious, the operation of both forms is precisely the same, while the constructions 60 are equivalent.

Referring now again especially to the form illustrated in Figs. 1 to 3, inclusive, I provide a suitable fitting 11 on the end of the pipe 10, to which are secured the two tubes 12 and 13, one of these tubes (in this particular arrangement) being inclosed within the other, so that the main fluid-conductor is the annular space between the two through which the fluid passes to the ordinary faucet 14, which is shown as the outlet or fluid-delivery device. Within the inner tube 13 is a cartridge-shaped traveling valve 15, which is adapted to be forced up said tube into contact with a seat provided therefor in the fitting 16, which constitutes the upper 65 end of the structure of which the tubes 12 and 13 are the body. As is obvious, when this seating takes place the flow of fluid is 70 shut off, except so far as a slight leakage is permitted, by the groove or some similar 75 equivalent formation. The traveling valve 15 is actuated by the pressure of the fluid passing through a small perforation 17 in a transverse partition 18, forming part of the 80 structure and located at the lower end of the 85 tube 13. This perforation 17 is made adjustable in size by means of the needle-valve 19. Surrounding the perforation 17 I provide other perforations 20. In a small chamber situated below the partition 18 is a washer 21, 90 (preferably of leather or rubber,) having a single central opening, so that the central perforation 17 shall never be obstructed thereby, but imperforate as to the remainder, so that when it is in contact with the 95 under side of the partition 18 the holes 20

therein shall be closed thereby. The central orifice in this washer is of considerably less diameter than the diameter of the opening leading thereto from below, so that a considerable portion of its under surface is exposed to the force of the fluid coming toward it through the pipe 10, and thus said washer is raised against the said partition 18 by said force except when there is a greater pressure thereon from the fluid from the other side.

The operation of my apparatus is as follows: The various devices being at rest and in the positions shown and it being desired to draw the predetermined quantity of fluid, 15 the fluid-outlet, as the faucet 14, is opened, whereupon the fluid will begin to flow in the regular and ordinary manner therethrough. Pressure above the traveling valve 15 being reduced, the pressure of fluid passing in 20 through the orifice 17 will begin to force said traveling valve upwardly. At the same instant the fluid-pressure will cause the washer 21 to rise against the under side of the partition 18, thus closing the perforations 20.

25 As the quantity of fluid passing through the orifice 17 is small, the traveling valve 15 will move slowly, its speed being governed by the size of said orifice, which, as above stated, may be regulated by means of the needle- 30 valve 19. When said traveling valve reaches its seat, however, it of course at once stops the flow of fluid and will remain seated, thereby preventing the flow of any more fluid so long as the fluid-outlet is open, so that no pressure 35 can accumulate above said traveling valve. When the fluid-outlet is closed and the pressure above the traveling valve becomes equalized with the pressure below or behind it, (which occurs very shortly on account of the 40 slight leakage which is permitted past said traveling valve when seated,) then the traveling valve will begin to descend because of its own gravity and will presently arrive at its initial position just above the partition 45 18, as will be readily understood. The descent is rendered more rapid than the ascent by reason of the holes 20 in the partition 18, these being uncovered and put into condition to permit the fluid to pass by reason of 50 the washer 21 dropping away and leaving them free, which it will do as soon as the traveling valve begins to descend, the descent of said traveling valve causing a slightly

greater pressure above than below said washer.

Having thus fully described my said invention, what I claim as new, and desire to secure by Letters Patent, is—

1. The combination in a fluid-supply system of a fluid-outlet, a fluid-supply leading thereto, a valve-seat behind the outlet between it and the main fluid-supply, a second tube or pipe below said valve-seat, a traveling valve therein, a horizontal partition near the lower end of said tube or pipe containing perforations, a traveling washer formed to cover certain of said perforations and leave part of said perforations uncovered, which washer is mounted to move back and forth in a chamber below said partition and is adapted to be operated by the water-pressure to close against said partition when the fluid is flowing through the apparatus and the traveling valve is rising and to separate therefrom and leave the perforations open when the valve is descending, substantially as set forth.

2. The combination in a fluid-supply system of a fluid-outlet, a supply-pipe leading thereto, a valve-seat behind the outlet, a second pipe below said valve-seat, a traveling valve therein, a horizontal partition near the lower end of said pipe containing perforations, a needle-valve projecting into one of said perforations for varying its size, a traveling washer mounted in a short chamber beneath said chamber and formed to cover the perforations therein except the one provided with said needle-valve, which washer is mounted to travel back and forth in said chamber below said partition and is adapted to be operated by the water-pressure to close against said partition when the fluid is flowing outwardly through the apparatus and the traveling valve is rising and separate therefrom and leave the perforations open when said traveling valve is descending, substantially as set forth.

In witness whereof I have hereunto set my hand and seal, at Indianapolis, Indiana, this 14th day of January, A. D. 1902.

JOSEPH W. NETHERY. [L. S.]
